VISIBLE LOOSE LEAF DEVICE

Filed May 31, 1928

UNITED STATES PATENT OFFICE

CHARLES A. FINLEY, OF RUTHERFORD, NEW JERSEY, ASSIGNOR TO BOORUM & PEASE COMPANY, OF BROOKLYN, NEW YORK, A CORPORATION OF NEW YORK

VISIBLE-LOOSE-LEAF DEVICE

Application filed May 31, 1928. Serial No. 282,015.

This invention relates to visible loose leaf devices and more particularly to panels in which visible index cards are slidably mounted in overlapping relation. One object of the invention is to provide a panel which will facilitate the interengagement of the cards in the panel.

Another object of my invention is to make a panel which is thin enough to be removably mounted in a binder. Another object of my invention is to make a simple panel which will grip the cards when they are not being changed but which at the same time will quickly and easily release that pressure when desired.

In the drawings:

Fig. 1 is a plan view of a panel constructed according to my invention, part of the panel and some of the cards being broken away;

Fig. 2 is a vertical section through the panel and the cards taken on the line 2—2 of Fig. 1;

Fig. 3 is a vertical longitudinal section taken on the line 3—3 of Fig. 1 looking in the direction of the arrow.

Fig. 4 is a vertical cross section of one edge of the panel taken on the line 4—4 of Fig. 1, showing card racks on both sides of the panel.

Fig. 5 is a plan view of a card adapted to be used in the panel.

Fig. 6 is an exaggerated vertical longitudinal section taken on the line 6—6 of Fig. 1.

In visible indexes it is highly desirable to have means for carrying the cards which are thin enough to be used as leaves in a loose leaf binder such for instance as the magazine binder type of construction and which are at the same time simple and efficient in their construction and operation. According to the embodiment of my invention shown in the drawings, the cards are carried in a panel 1 consisting of a board 4 and a rack or racks 10 carried thereon. The board may, if desired, carry the pins 5 at each end to permit mounting of the panel in a magazine binder of the type for instance shown in the U. S. patent granted to Bolling

1,494,730, May 20, 1924; if desired the panel may be provided with a suitable hinge 13.

The rack may consist of a thin sheet of metal having punched up therefrom flanges 11 running lengthwise of the panel and forming inwardly facing grooves spaced apart about the maximum width of the body of the cards. The rack may be riveted to the board 4 by means of rivets 3 at each corner of the rack and I prefer to place at the top and bottom of the flanges underneath same a cross-bar or stop 6 which can be riveted in position to close the ends of the flanges and prevent the cards from sliding out of the panel. These bars 6 can be riveted in position by means of rivets 2 and these rivets 2 can, if desired, be used to fasten the rack to the panel. A rack can be fastened on each side of the panel, if necessary, thus increasing the capacity of the panel, as shown in Fig. 4.

It will be observed that by means of thus striking the flanges up from the integral piece of sheet-metal, the space under the flanges is deeper than the thickness of the metal and extends downwardly to a greater depth, forming a channel 15. This channel, recessed with relation to the upper surface of the floor 9 of the rack, is an important feature of my invention and especially so when used in connection with hinged cards 12 having ears 14 at their sides for suspending means. I will show and describe the invention in connection with the depending ear card which forms the subject matter of the patent granted to Alwin Von Auw on November 15, 1927 under Number 1,649,763 with which type of card the invention is peculiarly useful. Each ear 14 of that card consists essentially of an oblong portion outside of and severed from the body of the card from the lower end of the ear up to a point 20 perhaps $\frac{1}{4}$ of an inch from the top of the card. The body of the card is hinged at 16, the hinge line preferably joining the upper ends of the lines of severance between the ears and the card. In the drawings a slot is shown extending partially along the hinge line 16, but not quite to the points of severance 20. The use of a slot

is optional. The reinforced card shown in Fig. 5 forms the subject of Von Auw application Ser. No. 285,581, filed June 15, 1928, and is one of the variations of the general type of depending ear card, in connection with which my invention is particularly useful as stated above.

The center portion of the rack plate 10, i. e., the portion between the upstruck flanges may be termed a floor 9 and if made of resilient material performs a peculiarly useful function in holding the cards in the panel. When cards are mounted in the panel as shown in Fig. 1, with ears or other portions thereof underneath the flanges 11, this floor 9 pressing upwardly against the cards tends to grip them between the edges of the floor and the free edges of the flanges 11. This holds the cards in their desired position without the use of any additional elements and at the same time provides a grip on the cards which can be released by a mere pressure of the fingers anywhere on the cards or floor. If it is desired to make the rack of a non-resilient sheet, a spring 17 (Fig. 6) or other resilient means may be placed under the floor 9 to give it resiliency for this purpose, such means being placed underneath the edges of the floor or at any other desired point. I believe that I am the first to thus grip the cards in the rack.

With many devices of index cards it is necessary in order to properly engage the cards with each other to have certain portions thereof pass to a certain side of the adjacent card, and in the panel which I have just described having the channel, efficient means are provided for insuring that the elements of the card at each side thereof properly interengage with the adjacent cards. With the type of card shown in the above mentioned Von Auw patent, there is a depending ear 14 at each side of the card 12 which is adapted to be depressed to pass behind the ear of the card below in order to provide proper interengagement of these hinged cards in the panel. This depending ear, whose lower end is free from the body of the card, will lie in the channel near the bottom thereof and as any card is brought down on its neighbor already in the panel, the depth of the channel will allow that depending portion of the ear to pass under the upper edge of the card below more readily than in a panel lacking my channel.

The construction requires only a few operations to make it, and consequently economizes in the time and labor of manufacture. The ability to attach a rack to each side of the panel and to attach both racks in one operation and by one set of rivets is another saving in material.

In using the device, as the cards are slid up or down upon the panel, the bodies of the cards lie upon the floor 9 of the rack,

and they are readily kept in alignment by the fact that their edges are guided by the facing edges of the flanges. The ears, lying in the channels under the flanges, have their lateral edges guided on the one side by the edge 19 of the floor 9 of the rack, where the flange was sheared up, and on the other side by the edge 18 of the channel formed where the flange is offset from the remainder of the rack. The floor of the channel is the board 4, and the roof of the channel is the flange 11.

What I claim is:

1. A visible index panel having inwardly facing opposed flanges, cards having portions underlying said flanges and a spring metal floor between said flanges exerting an upward pressure on the cards and tending to grip them between itself and the flanges. 80

2. A visible index comprising a panel having a rack having inwardly facing opposed flanges, resilient means between said flanges tending to hold the cards in the rack at a higher level than the bottom of the space under the flanges and cards lying above said resilient means and having portions underlying said flanges. 90

3. A visible index panel comprising a rack having inwardly facing opposed flanges, cards having ears underlying said flanges and a floor between said flanges forming channels underneath the flanges recessed with relation to the upper surface of said floor. 95

4. A visible index panel comprising cards with lateral depending ears in combination with a rack having inwardly facing opposed flanges integral with said rack struck up therefrom, under which the ears of said cards are adapted to lie, in combination with a floor forming an integral part of said rack lying between said flanges and of a width not sufficient to underlie the ears of said cards, the rack having a space lower than said floor underneath the struck-up flanges. 100

5. A visible index comprising a panel having a rack, a floor forming part of said rack, inwardly facing opposed flanges struck up from said rack, there being channels under said flanges having bottoms lower than said floor, in combination with cards having a body portion and depending ears, the body portion of said cards overlying said floor, and the depending ears lying in said channels and adapted to interengage therein. 115

6. A visible index comprising a panel having a rack, a floor forming part of said rack, inwardly facing opposed flanges struck up from said rack forming channels under said flanges having bottoms lower than said floor, in combination with a series of overlapping hinged cards each comprising a body portion overlying the body portion of 120

the card below and a depending ear integral with the body portion at each side thereof adjacent its upper edge underlying the corresponding ear of the card below, there being a hinge line joining the upper ends of the lines of severance between the ears and the cards, the body portion of said cards overlying said floor, and the depending ears lying in the channels under said flanges.

5 10. A visible index comprising cards with lateral ears in combination with a rack comprising a resilient floor and inwardly facing opposed flanges integral with said rack, the resilient floor lying between said flanges, and cooperating therewith to grip the cards.

15 8. A visible index comprising cards with lateral ears in combination with a rack comprising a resilient floor and inwardly facing opposed flanges integral with said rack covering channels under said flanges the resilient floor lying between said flanges, and cooperating therewith to grip the cards, the bodies of said cards overlying the floor and lying between said flanges and the ears 20 of said cards lying in the channels under said flanges.

25 9. A visible index comprising cards with lateral ears in combination with a rack comprising a resilient floor and inwardly facing opposed flanges integral with said rack, the resilient floor lying between said flanges, and by its resiliency enabling said rack to grip said cards between the edges of the floor and the inner edges of said flanges.

30 35 10. A visible index comprising cards with lateral ears in combination with a rack comprising a resilient floor and inwardly facing opposed flanges integral with said rack covering channels under said flanges, the resilient floor lying between said flanges and the body of said cards overlying the floor and lying between said flanges and the ears of said cards lying in the channels under said flanges, the resiliency of the floor 40 45 enabling the rack to grip said cards, for the purposes set forth.

50 11. A visible index comprising cards with lateral ears in combination with a rack comprising a resilient floor and inwardly facing opposed flanges integral with said rack covering channels under said flanges, the resilient floor lying between said flanges and the body of said cards overlying the floor and lying between said flanges and the ears of said cards lying in the channels under said flanges, the resiliency of the floor 55 enabling said rack to grip said cards at the juncture of the ears to the bodies of said cards.

60 12. A visible index comprising cards with lateral ears in combination with a rack comprising a floor, inwardly facing opposed flanges integral with said rack, said flanges 65 covering channels and resilient means in

said floor between said flanges, enabling said rack to grip the cards.

13. A visible index comprising a rack having a resilient floor and inwardly facing opposed flanges integral with said rack and covering channels, in combination with a series of overlapping hinged cards each comprising a body portion overlying the body portion of the card below and a suspending and spacing portion including a depending ear at each side of the body portion adjacent its upper edge, each ear partially underlying the corresponding ear of the card below and underlying the flange and sliding longitudinally in the channel under the flange, said resilient floor lying between said flanges, and by its resiliency enabling said rack to grip said cards between the edges of the floor and the inner edges of said flanges at the juncture between the ears and the bodies of said cards.

In testimony whereof I have signed my name to this specification.

CHARLES A. FINLEY.
